Filed May 17, 1960, Ser. No. 60,618

Term of patent 14 years

(Cl. D26—14)

FIG. 1

FIG. 2

FIG. 3

Figure 1 is a bottom perspective view of a combined phonograph pickup cartridge and mounting bracket therefor, showing my new design;

Figure 2 is a top perspective view thereof; and

Figure 3 is a side elevation thereof, to an enlarged scale and partly in cross section taken along the section line III—III of Figure 2, the opposite side being substantially a mirror image thereof.

The broken line showing of legible matter in the drawing is for illustrative purposes only.

I claim:

The ornamental design for a combined phonograph pickup cartridge and mounting bracket therefor, as shown and described.
